[57] CLAIM

The ornamental design for a roadway luminaire, as shown and described.

DESCRIPTION

FIG. 1 is a perspective view looking obliquely down at the front end of a roadway luminaire embodying our new design; and

FIG. 2 is a perspective view looking obliquely up at the rear thereof.

FIG. 3 is a side elevational view thereof.

The luminaire is symmetrical about a medial vertical longitudinal plane. Environmental structure is shown in broken lines for illustrative purposes only.
